Des. 235,550
Patented June 24, 1975

235,550

DENTAL BLADE PROBE TOOL

Robert Philip Berger, 17110 Clemons Drive,
Encino, Calif. 91316

Filed Dec. 29, 1969, Ser. No. 20,651

Term of patent 14 years

The term of this patent subsequent to Feb. 24, 1986,
has been disclaimed

Int. Cl. D24—02

U.S. Cl. D24—1 D

FIG. 1 is a perspective view of a dental blade probe tool showing my new design;

FIG. 2 is a side elevation thereof;

FIG. 3 is a top plan view thereof;

FIG. 4 is an end elevation thereof; and

FIG. 5 is an enlarged fragmentary view of the gripping surface of the dental blade probe tool.

I claim:

The ornamental design of a dental blade probe tool, substantially as shown.
